UNITED STATES PATENT OFFICE.

CHARLES J. KLEIN, OF MILWAUKEE, WISCONSIN.

MEANS FOR SECURING CONTACTS.

1,143,633.

Specification of Letters Patent. Patented June 22, 1915.

Application filed October 28, 1913. Serial No. 797,872.

To all whom it may concern:

Be it known that I, CHARLES J. KLEIN, a citizen of the United States, residing at Milwaukee, in the county of Milwaukee and State of Wisconsin, have invented new and useful Improvements in Means for Securing Contacts, of which the following is a full, clear, concise, and exact description, reference being had to the accompanying drawing, forming a part of this specification:

This invention relates to electric contacts and more particularly to improved means for securing the same to their supports.

As is well known, the contacts of electric switches, and especially the stationary contacts of snap switches, are often subjected to strain by the movable contactor upon operation of the switch, with a consequent liability of displacement.

One of the objects of my invention is to provide simple and efficient means to solidly anchor such resilient stationary contacts.

A further object is to provide simple and practical means whereby such contacts may be rigidly held to their supports by the use of single screws.

Another object is to provide means adapted to hold such contacts against rotation about their securing screws and at the same time to wedge said screws against loosening.

In order to more fully disclose my invention I have illustrated the preferred embodiment thereof in the accompanying drawing.

In the drawing, Figure 1 is a top plan view of the contact; Fig. 2 is a side view of the same in initial position upon a support; and, Fig. 3 is a similar view of the same when secured to the support.

The contact comprises a contact portion 1 and a base portion 2 at right angles to the contact portion. If desired, the contact may in practice be resilient or rigid and disposed at any angle to the base. The base 2 is preferably annular and provided with an aperture 3 to receive a securing screw 4 for mounting the same upon a support 5, for example, an insulating block.

The annular base 2 is split at one side, as

at 6, and the adjacent ends 7 and 8 thereof are bent slightly downwardly. The base is thus substantially flat except for the V-shaped resilient depression at one side.

The support 5 is provided on its upper face with a V-shaped recess 9 to receive the bent prongs 7 and 8 of the contact base. An aperture 10 extends through the support adjacent the recess 9 for the securing screw 4. In practice, the support may also be provided with a recess 11 in its lower face to receive a nut 12 into which the threaded end of the screw 4 is threaded.

The angle of depression of the prongs 7 and 8 is slightly greater than the angle of the recess 9, as shown in Fig. 2. When the contact is being mounted, the head of the screw 4 thus presses the bent portions 7 and 8 of the contact base firmly into the recess 9 and locks the contact against turning. Due to the difference in the V-angles or depths of the support recess 9 and the bent portions 7 and 8, the latter are resiliently tensioned by the screw head when the same is screwed home and thus wedge the screw against loosening in the support.

While I have illustrated and described herein the preferred form of my invention, it is to be understood that the same may assume other forms without departing from the scope of the appended claim.

What I claim as new and desire to secure by Letters Patent is:

In combination, a contact having a substantially flat base with a resilient portion inclined thereto, and an insulating block for said base having a recess with an inclined face to receive said resilient portion, the inclination of said resilient portion being greater than the inclination of said recessed face whereby said resilient portion is compressed when said base engages said block.

In witness whereof, I have hereunto subscribed my name in the presence of two witnesses.

CHARLES J. KLEIN.
